UNITED STATES PATENT OFFICE.

DAVID WILLIAMSON, OF NEW YORK, N. Y.

IMPROVEMENT IN BREECH-LOADING FIRE-ARMS.

Specification forming part of Letters Patent No. 58,525, dated October 2, 1866.

To all whom it may concern:

Be it known that I, DAVID WILLIAMSON, of the city and county and State of New York, have invented certain new and useful Improvements in Breech-Loading Fire-Arms; and I do hereby declare that the following is a full, clear, and exact description of the same, reference being had to the accompanying drawings, and to the letters of reference marked thereon.

In the annexed drawings, making part of this specification, A represents the stock and B the barrel of the piece. A portion of the under side of the barrel is provided with a dovetail, which fits in a groove in the stock, so as to allow the barrel to have an endwise-sliding motion on the stock when desirable.

The butt of the barrel is formed for receiving fixed ammunition.

a represents the stop which secures the barrel in its place when the piece is in condition for firing, and which also serves for drawing out the exploded metallic cartridge. This stop consists of a small cylindrical piece of metal, hollow from near its top to its bottom, as shown, with a small coiled spring, e, in the hollow, for the purpose of pressing said stop up against the barrel. On a portion of the upper end of this stop is a shoulder, the metal at the back of the shoulder being beveled, as shown in the figures. This shoulder on the stop catches into a notch in the under side of the barrel. The barrel at this point, where the stop strikes it, is beveled, as seen from o to o', to correspond with the bevel on the stop.

G represents a small lever, which is pivoted in the frame of the stock, one end of which lever passes through an opening in the guard, and the other end passing into a small opening in the stop a. By means of this lever the stop a may be operated when desired for freeing the barrel when it is wished to slide it forward.

E represents the trigger, which is pressed away from toward the stop by means of a small spring, d. This trigger is provided with a small pin or projection, which is pivoted or hooked to it at its upper end, which said pin extends toward the stop a, and when the piece is at any position except at half-cock catches under a shoulder on the side of stop a. When the piece is at half-cock this pin does not catch in the stop a, and said stop can then be pressed

down, so as to allow the barrel to pass back until its end touches the breech-piece. The upper end of the shoulder on the stop a serves to catch behind the flange of the metallic case in which the ammunition is placed, and to draw said case from the barrel when said barrel is slid forward.

C represents the hammer. This hammer is provided with two detonating lugs or points, i and n. The point i is intended for striking the ordinary fixed ammunition, while the point n is intended to strike a cap upon a nipple in a case, H. This case H can be loaded by any one having it, and will be discharged by the point n striking the cap upon its nipple. The hammer is also provided with two notches for cocking and half-cocking. The upper end of the trigger is formed so that it will catch into these notches as the hammer is raised. The notch for the trigger at half-cock is made deeper than the other, so that when in this position the pin x will not be pushed forward to catch the stop a.

D represents the mainspring, one end of which presses against the hammer, and the other against a notch in the frame of the stock.

J represents a screw, which passes through the stock near its forward end. The end of said screw passing into a groove in the under side of the barrel prevents said barrel from sliding only so far on the stock.

Having thus fully described my invention, what I claim as new, and desire to secure by Letters Patent, is—

1. The detached spring-stop a, used with the lever G and the under side of the barrel B, being so constructed and arranged as to act as a stop for the barrel and a direct retractor, substantially as specified.

2. The pin x upon trigger E, when used with stop a, for the purpose of locking the barrel and preventing it from being thrown up to or away from the breech except at half-cock, substantially as set forth.

In testimony that I claim the foregoing as my own I hereby affix my signature in the presence of two witnesses.

DAVID WILLIAMSON.
